Specification for Design.

Patented June 11, 1918.

Application filed December 3, 1917. Serial No. 205,268. Term of patent 14 years.

To all whom it may concern:

Be it known that I, WILLIAM C. LOEHRIG, a citizen of the United States, residing at Hartford, in the county of Hartford, State of Connecticut, have invented a new, original, and ornamental Design for an Adjustable Stock-Support, of which the following is a specification, reference being had to the accompanying drawing, forming part hereof.

In said drawings Figure 1 is a front eleva-

tion, and Fig. 2 is a side elevation of an adjustable stock support, showing my new design.

I claim:

The ornamental design for an adjustable stock support, as shown.

WILLIAM C. LOEHRIG.
